UNITED STATES PATENT OFFICE.

JOHN T. KING, OF MADISON, WISCONSIN.

INK-DISTRIBUTING APPARATUS FOR PRINTING-MACHINES.

SPECIFICATION forming part of Letters Patent No. 400,223, dated March 26, 1889.

Application filed April 21, 1888. Serial No. 271,446. (No model.)

To all whom it may concern:

Be it known that I, JOHN T. KING, of Madison, in the county of Dane and State of Wisconsin, have invented certain new and useful Improvements in Ink-Distributing Apparatus for Printing-Machines, of which the following is a specification, reference being had to the accompanying drawings, in which—

Figure 1 is a plan view. Fig. 2 is a section 10 on the line 2 2 of Fig. 1, and Fig. 3 is a section on the line 3 3 of Fig. 1.

My invention relates to ink-distributing apparatus in which a stationary ink-disk and a car traveling over it back and forth are employed to distribute the ink; and it consists 15 in an organization of parts, below described and claimed.

Referring to the letters upon the drawings, A indicates a car; B, the tracks; C, the ink-disk; E, the composition rollers; F, the grinding-rollers or screw vibrators, and G the slip-nuts, which are pivoted loosely to a shaft, H, so that the screw vibrators will be borne down by force of gravity upon the upper periphery 20 of the composition rollers. The composition-roller shafts have their bearings in slots I of posts K, secured to the car-frame. The slip-nuts engage by their upper surfaces with the screw-threads on the shaft ends of the screw 25 vibrators. The hole through the slip-nuts be-

ing larger than the diameter of the shaft ends, whenever the longitudinal movement of the screw vibrator meets with any obstruction the slip-nuts will rise up slightly, so as to disengage the threads and permit the rotation of 35 the screw vibrator.

I do not claim in this application the slip-nuts in combination with a threaded shaft and screw vibrator, because I have made that the subject of a claim in another application—to wit, No. 270,702, filed April 14, 1888; but,

Having described my improvements, what I do claim, and desire to secure by Letters Patent, is—

The combination, with a car for an ink-distributing apparatus, of the composition rollers, the screw vibrators, ²⁷ the slip-nuts loosely pivoted to the shaft H, so as to cause the screw vibrators to bear by the yielding 40 force of gravity upon the upper peripheries of the composition rollers, substantially as set forth.

In testimony of all which I have hereunto 45 subscribed my name.

JOHN T. KING.
